UNITED STATES PATENT OFFICE.

GEORGE A. WALKER, OF WAUKESHA, WISCONSIN.

DESIGN FOR A PORCH SHADE.

Application filed September 15, 1924. Serial No. 10,777. Term of patent 7 years.

To all whom it may concern:

Be it known that I, GEORGE A. WALKER, a citizen of the United States, residing at Waukesha, in the county of Waukesha and State of Wisconsin, have invented a new, original, and ornamental Design for Porch Shades, of which the following is a specification, reference being had to the accompanying drawing, forming a part hereof.

The drawing is an elevation of a porch shade comprised of wooden weft splints and spaced pairs of warp cords showing my new design.

I claim:

The ornamental design for a porch shade as shown and described.

GEORGE A. WALKER.
